UNITED STATES PATENT OFFICE.

THOMAS W. HUTCHINS, OF WYOMING, PENNSYLVANIA.

DESIGN FOR A FENCE-POST ANCHOR.

SPECIFICATION forming part of **Design No. 20,681**, dated **April 21, 1891**.

Application filed March 10, 1891. Serial No. 384,495. Term of patent 14 years.

To all whom it may concern:

Be it known that I, THOMAS W. HUTCHINS, of Wyoming, in the county of Luzerne and State of Pennsylvania, have invented and 5 produced a new and original Design for Fence-Post Anchors or Bases, of which the following is a specification, reference being had to the accompanying drawings, forming a part thereof.

10 Figure 1 is a perspective view of the anchor or base with a section of the post in place. Fig. 2 is a side elevation, and Fig. 3 is a top plan view of the base.

15 The same letters of reference indicate the same features in all the figures.

A fence-post base or anchor formed in accordance with my present design presents, generally, the appearance of an inverted pyramid having slightly-converging sides A, with 20 the apex or point removed and with projecting ledges or extensions B on two sides diametrically opposite each other. In cross-section the structure is rectangular, and the top surface is formed with a central concavity or 25 depression C, at the bottom of which an aper-

ture is formed for the reception of the post, which aperture extends way through the base from top to bottom. The ledges or extensions B are at or near the ends, and the surfaces E between the ledges and ends are flat and inclined toward the axis of the base in opposite directions. The diametrically-opposite faces of the base, not having ribs thereon, are made perfectly smooth and straight from top to bottom, giving a pleasing and symmetrical appearance to the structure. 30 35

What I claim is—

The fence-post anchor or base herein shown and described, having the pyramidal faces forming the body rectangular in cross-section with a substantially flat top and having ledges or projections on diametrically-opposite faces near the ends, with surfaces between said ledges and ends inclined toward the central axis of the body, substantially as described. 40 45

THOMAS W. HUTCHINS.
